UNITED STATES PATENT OFFICE.

ADAM EDWARD CHODZKO, OF LOS ANGELES, CALIFORNIA.

PNEUMATIC PUMPING APPARATUS.

1,071,878.

Specification of Letters Patent.

Patented Sept. 2, 1913.

Application filed June 29, 1908, Serial No. 505,067. Renewed January 28, 1913. Serial No. 744,777.

To all whom it may concern:

Be it known that I, ADAM EDWARD CHODZKO, a citizen of the United States, residing at Los Angeles, in the county of Los Angeles and State of California, have invented new and useful Improvements in Pneumatic Pumping Apparatus, of which the following is a specification.

The present invention relates to that class 10 of pneumatic pumping apparatus wherein water is raised by the expansive force of compressed air, said air being in immediate contact with the water.

The main object of the present invention 15 is to obtain in a pneumatic pumping apparatus of this class a condition of maximum efficiency.

A further object of the invention is to provide for the use of comparatively low 20 pressures in pumping irrespective of the height, thereby economizing not only in power but in the weight and cost of the apparatus.

Another object of the invention is to provide a unit or sectional construction which can be added to as desired, so that the same elements can be used for pumping apparatus for any height by taking the proper number of elements.

30 Other objects of the invention will appear hereinafter.

Mathematical investigation of the work done in raising water by pneumatic lift demonstrates that the working efficiency is 35 greater with a low pressure and a corresponding low lift than with a high pressure and a corresponding high lift. In other words, a greater mechanical efficiency is obtained by lifting the water pneumatically in 40 a series of stages than by lifting the water the same distance in a single stage.

My invention provides for obtaining maximum working efficiency by using under all circumstances very moderate values of the 45 lift and of the air pressure, by dividing up the total lift regardless of its height into a number of equal and separate sections or cells whose length may be taken as small as desired and the water in transit from the 50 source of supply to the point of delivery passing in succession through all of the cells, so that each cell receives the water from the next one below and delivers it into the next one above and has an independent supply 55 of compressed air and an independent discharge of waste air, the pressure of com-

pressed air being only that required for the operation of one cell, whatever the total lift may be. Since the same operation proceeds in each cell, the efficiency of the apparatus 60 as a whole is the same as the individual efficiency of each cell.

My invention is applicable to a pumping apparatus for any purpose and will herein-after be described with reference to a min- 65 ing pump and to a well pump.

The accompanying drawings illustrate the invention, and referring thereto: Figure 1 is a diagrammatic view illustrating the principle of the invention. Fig. 2 is a side elevation of a portion of a mine shaft pump embodying the invention. Fig. 3 is a section on the line x^3-x^3 in Fig. 2. Fig. 4 is an enlarged section on the line x^4-x^4 in Fig. 5, of a portion of the apparatus at the 70 joint between two successive sections. Fig. 5 is a section on the line x^5-x^5 in Fig. 4. Fig. 6 is a vertical section on the line x^6-x^6 in Fig. 7 of the valve device controlling ad- 75 mission of air to the cell. Fig. 7 is a sec- 80 tion on the line x^7-x^7 in Fig. 6. Fig. 8 is a side elevation; and Fig. 9 is an end elevation, partly in section, of the upper part of a well embodying the invention and a lifting head therefor. Fig. 10 is a vertical 85 section of adjacent portions of two sections of the construction shown in Figs. 8 and 9. Fig. 11 is a transverse section on the line $x^{11}-x^{11}$ in Fig. 10. Fig. 12 is a transverse section on the line $x^{12}-x^{12}$ in Fig. 10. Fig. 90 13 is a transverse section on the line $x^{13}-x^{13}$ in Fig. 10. Fig. 14 is a transverse section on the line $x^{14}-x^{14}$ in Fig. 10. Fig. 15 is a vertical section of the air admission valve for this form of the invention. Fig. 95 16 is a plan of said valve.

The principle of the invention may be de- 100 scribed with reference to Fig. 1, where 1 designates the body of water or source of supply from which water is to be raised by the pumping apparatus. The apparatus comprises a series of units or a plurality of cells a, b, c, d , etc., connected in series. Each cell comprises an upwardly extending education leg 2 and a downwardly extending 105 submergence leg 3 connected at its upper end to the upper end of the education leg and extending downwardly about half the height of the education leg. The education leg of the lowermost cell a opens at its lower 110 end into the body of water 1 which takes the place of the submergence leg for that

cell, and the eduction leg of this and of each succeeding cell *b*, *c*, etc., opens at its upper or delivery end into the submergence leg 3 of the succeeding cell. The eduction leg of the uppermost cell forms the final delivery for the water. The independent air supply for the respective cells is provided by a pipe 5 having branches 6 leading to the bottom of the respective eduction legs of the series of cells and an independent or separate discharge 7 is provided at the top of each cell, that is to say, at the top of the eduction and submergence legs.

The general operation is as follows: The lower cell is assumed to be immersed in the body of water 1 to an extent sufficient to cause the water to rise in the eduction leg to about the level of the bottom portion of the submergence leg of the cell *b*. Air being supplied through the pipe 5 under sufficient pressure, it passes up through the water in the eduction leg 2 of the cell *a* and by mixture therewith decreases the specific gravity of the contained fluid to an extent sufficient to enable the body of water 1 on the outside to raise the column of water in the said eduction leg to the top of said leg and to cause it to flow over into the submergence leg of the second cell *b*, the water passing from this submergence leg of the second cell by gravity to the lower part of the eduction leg of the second cell to fill the same to about the level of the bottom of the submergence leg of the next cell. At the same time the compressed air that has been rising with the water has expanded so that its effective pressure is entirely spent when the mixture of air and water reaches the top of leg 2; the expanded or "dead" air being exhausted into the atmosphere, the water alone falling into cell *b*. The air supplied from the pipe 5 through the branch 6 to the bottom of the eduction leg 2 of the cell *b* then operates in similar manner to raise the water to the top of cell *b* and to fill the submergence leg 3 thereof and so on, until the water is finally delivered at the uppermost eduction leg 2. It will be noted that the submergence leg of the first cell *a* is constituted by the body of water 1.

In the practical operation of an apparatus constructed on the above described principle some difficulties arise, as follows: Before the apparatus has been primed there will be a free outlet of air through each pipe 6 and, therefore, no pressure could be maintained sufficient to lift the water at the lowermost cell. It is necessary, therefore, to provide means for shutting off the supply of air to any eduction pipe until there is sufficient head of water thereover to prevent escape of air except as required for the lifting operation. Provision must also be made for adapting the apparatus for

work under considerable variations of height in the source of supply.

In applying the invention to a mine shaft where there is in general sufficient room for the provision of an air supply pipe external to the column of lifting cells the constructions shown in Figs. 2 and 7 may be adopted. In said figures 11 designates a support consisting of two rails or sills extending in the shaft in position to support the cell and the air supply. The lifting apparatus is constructed in sections which are detachable so as to provide for unit construction and for convenience, each unit of the construction embodying parts of two successive cells. Each structural unit or section of the apparatus comprises a tubular member 3 consisting of a flat rounded shell of sheet iron having heads 14, 15 at the lower and upper ends thereof, a pipe 12 extending through the lower head 14 and extending nearly to the upper head 15 and another pipe 12' extending downwardly through the upper head 15 and nearly to the lower head 14. Successive units or sections are placed on top of one another, so that the top of each pipe 12' of any unit communicates with the bottom of the pipe 12 of the next upper unit. For making this connection any suitable separable joint may be used, for example, that shown in Fig. 4 consisting of two glands 16, 17, surrounding the tubes 12, 12', packing 18 within said glands over the joint, and pivoted clamp bolts 19 adapted to draw the glands together to compress the packing at the joint. When the parts are assembled as stated the pipe 12' of each unit, together with the pipe 12 of the next higher unit, constitutes the eduction leg 2 of a cell, the tubular member 3 of the said next higher unit constituting the submergence leg of said cell. The tubular members 3 may be supported on the sills 11 by cross bars 20 secured to said sills and angle irons 21 fastened to the said tubular members and resting on the cross bars. Air outlets 7 are provided in heads 15.

The air supply pipe 5 is supported on the sills 11 by straps 24 fastened to said sills and extending under the said pipe. The branch air pipe 6 communicating with the pipe 5 leads to a Y-fitting 26 formed as a chamber on the bottom of the bottom plate 14 of the tubular member 3, said chamber having two extensions 26', extending respectively to the right and left of the tubular member, so as to provide for alternate connection to successive sections, it being understood that the eduction pipes of the successive sections are arranged right and left, as shown in Fig. 3. One branch 26' for each section is connected to the air supply branch pipe 6 and the other branch 26' is closed by a screw plug 27. From the chamber 26 a nozzle connection pipe extends 130

upwardly into the eduction pipe 12 for that section. This nozzle connection pipe 29 is provided with lateral openings 30 communicating with the chamber 26 and the upper end of the pipe 29 extends into and communicates with a valve casing 31 having a lower recess 32 communicating with the pipe 29 aforesaid, an upper recess 33 coaxial with the recess 32 and with the casing, and a partition 35 between said recesses. Passages 36 within the casing 31 lead from the lower recess 32 to the upper recess 33. A pipe 38 screwed into the upper recess 33 extends upwardly within the eduction pipe 12 and is connected at its upper end with an intermediate valve casing 31 similar to that just described and another pipe 40 is screwed into the upper end of the intermediate valve casing 31 and into the lower end of the top valve casing 31 whose upper end is closed by a screw plug 43, this upper valve casing being at about the level of the top of the corresponding section. In each valve casing 31 is provided a valve plug or piston 45 sliding in a vertical cylindrical chamber 46 extending upwardly from the lower recess 32, a spring 47 being provided resting on a cross pin 59 and pressing upwardly on said valve member, and a spring 48 pressing downwardly on said valve member. Valve casing 31 is formed with an annular chamber 49, said chamber surrounding, and communicating by a circular port 50 with, the cylindrical space 46 and having lateral outlets 51 opening outwardly and upwardly into the eduction pipe to serve as nozzle openings. Valve casing 31 is further provided with ports or passages 53 for establishing communication between the eduction pipe and the space within the cylindrical chamber 46 above the piston valve. Piston valve 45 has an upward projection 55 serving to limit the upward movement of the valve and is provided with lateral ports 56 for communicating with the aforesaid annular port 50, the lower portion of the piston valve being formed as a cylinder open at the lower end, so that said lateral ports communicate with the space 32.

In the lowermost cell or unit the pipe 12 is omitted, the bottom of the tubular outer member 3 having a strainer 58, connected thereto in place of said pipe, said strainer serving to admit water from the sump or body of water 1, to partly fill the said tubular member which acts as a submergence member for this first cell.

The air supply pipe 5 may be open at its lower end, as the pressure in said pipe is always less than the head due to the submergence, and with such a construction, any liquid escaping into said pipe will run into the sump.

The operation of the valve device is as follows: Assuming that there is no air pres-

sure or water pressure on the valve, the spring 47 pushes the valve 45 upwardly to position shown in Fig. 6. On account of this emergence of the lowermost valve 31 in the sump, water will flow through the passages 53 on to the top of the piston 45 thereof, and depresses said piston to lowermost position. If now the compressed air be turned on through pipe 5 and branches 6, it will enter through the channel 32 and press upwardly on the piston of each of the valves 31. In the case of all the valves which are not submerged this action of the compressed air will simply press the valves more strongly upward, this being the normal position, with the valves arrested by the stop 55 engaging with the partition 35, and in this position the side wall of the piston cuts off egress of air through the ports 50 of all of said valves so that air pressure is maintained in the air supply pipe notwithstanding the fact that there is no head of water in the upper cells at this time. In the case of the lowermost cell which is submerged, the compressed air entering the lowermost valve 31 presses upwardly on the piston 45 thereof and raises it again sufficiently to bring the lateral port 56 of the piston opposite the fixed port 50 allowing compressed air to flow out through the nozzle openings 51 and to consequently raise the water by pneumatic lifting action. The pressure of air supplied is just sufficient to overcome in conjunction with the normal pressure of the spring 47, a head of water equal to the height of a cell and as the upper and lower areas of the piston are equal, the result would be to move the piston to uppermost or normal position if it were not for the action of the spring 48, together with that of the water pressing on top of the valve 45, which unbalances the action so that when the water in the sump is just to the top of the lowest cell, the valve 45 will occupy the position stated with the ports 56 and 50 in register permitting escape of the air through the lowermost valve. With a stated height of water the pressure on the valves 31 at mid-height and at the top of the lowermost cell is sufficiently less than the pressure at the lowermost valve to allow the compressed air acting on the lower face of the pistons of said middle and upper valves, together with the action of the spring 47 thereon, to move said valves upwardly a sufficient distance to bring the ports 56 out of register with the ports 50, thereby cutting off the air supply through said middle and upper valves.

Let us now consider cells *a* and *b*: at normal submergence, water enters through the strainer 58 and fills it to the level of the sump, its contents being transferred to the cell *b* by the operations of valve 31, as just explained. Suppose now that for some rea-

son, the water level rises from that indicated at 61 to that indicated at 62, which is at a height equivalent to the height of one cell above the intermediate valve 31 in the lowermost cell. If air is turned on, the lowermost valve 31 opens automatically, but the air pressure not being sufficient to overcome the new submergence, the pump would not start with the valve. This objection is met by the extension of the air pipe of this valve to the second or intermediate valve 31, located midway between lower valve 31 and level 61, and whose spring is set to open air ports as soon as the level rises above 61. With the new level, we now have two valves open. The mixture of air and water must reach the top of the cell and under the increased submergence, the lowermost valve alone could not accomplish it; but the increased buoyancy induced in pipe 12 by the double air delivery allows the lowermost valve to operate under the increased submergence, and this will last until level 62 is reached in the sump, midway up cell b. Past that point, the second valve 31 is in the same condition as formerly was the lowest valve 31, and the third valve 31 located at the top of the cell begins to act and, in conjunction with the valve will work the pump for a range of variation of level from 62 to 63 when cell b is entirely flooded, and becomes the initial cell, instead of the cell a. The pump will start, therefore, under all possible conditions of water level; an objection might be raised, however, on the ground of excessive air consumption when two, and still more, three valves are blowing simultaneously. That objection is met by the use of the back spring 47 which acts after the effect of spring 48 has ceased. As the submergence increases, the downward motion of the valve continues, and it again closes the port while the two upper valves alone are in action. The object of the two springs 47 and 48 is therefore to tend to hold the valve into an intermediate operative position under the proper balance of air pressure and water pressure, and to move the valve to close the same on departure either way from this condition of balance, the valve moving upwardly against the spring 48 when the air pressure is in excess, for example, before the cells are primed and moving downwardly against the spring 47 under the excess air pressure when the submergence exceeds the height of one cell. The operation of the pump is therefore entirely automatic: it readily appears that any cell may, in a few moments, be disconnected from the cells above and below it, and from the air main after the supply thereof has been previously shut off, unions 39 being provided for the air connections 6. As each cell rests on the frame by means of angle brackets 21 riveted to shell 3 at its ends, the

disconnected shell may be shoved sidewise, its air pipe disconnected, the row of valves 31 pulled out through the top of pipe 12, cleaned or changed and the cell slid back into place without touching the rest of the 70 pump.

The form of the invention shown in Figs. 8 to 16 is specially adapted to cases where the space is limited, as in the case of a well where there is no space for the passage of 75 an air supply pipe external to the casing and it becomes necessary or desirable to utilize the space within the casing itself as a means for air supply. The well casing is formed in a plurality of sections detachably 80 connected to form a column, each section comprising an outer shell or casing member 65 and an inner shell 66, said shells being fastened to upper and lower heads 67, 68, so as to form an intervening space 69 which 85 serves as the air conveying space, and two eduction pipes 70, 71 are provided within the inner shell 61, said inner shell being made of elliptical form, as shown in Fig. 11. Each inner pipe 71 extends nearly to the 90 bottom of each section, as shown in the upper section at the right hand of Fig. 10 and at its upper end extends through the lower head 68 of the next upper section, as shown at the lower left hand side of Fig. 10, it 95 being understood that the connections and dispositions of the pipes 70, 71 are alternated right and left in the successive sections. The pipe 70 in each section extends through the lower head 68 of said section 100 and communicates with the upper end of the pipe 71 of the next lower section, the upper end of the pipe 70 terminating short of the upper end of the section, as shown at the lower right hand side of Fig. 10. The upper 105 head 67 of each section has an air discharge opening 72 directly above the open upper end of pipe 70.

To facilitate separation of the sections, they are preferably constructed as shown in Fig. 10, the heads 68, 67 having rabbets or shoulders 74 to match corresponding shoulders on an intermediate ring 76, said ring being formed with a separable portion 78 fastened by bolts 79. Rubber bands 80 115 are provided at the matched joint to seal the same under the action of the air pressure. A detachable joint is also provided between each pipe 71 and the superjacent pipe 70, said pipes having, respectively, 120 ferrules 82, 83, pressed or secured thereinto with a rubber band 84 sealing the joint between them, said rubber band being clamped by a split clamp ring 86 fastened by clamp bolt 87. By moving the member 125 78 of the outer ring access may be obtained to the clamp device 86 to loosen the same, so that the clamp ring and rubber band may be slipped onto, say, the upper ferrule 83, leaving the parts free for detachment, in- 130

spection and repair. A valve 88 is provided in the lower head 68 of each section, said valve performing the same functions as the valve 31; above referred to and comprising a casing with a cylindrical central bore 90, a slide valve 91 fitting therein, a stop 92 limiting the upper movement of the valve, a spring 93 for pressing the valve downwardly, a spring 94 for pressing the valve upwardly, a cross pin or stop means 95 for limiting the downward movement of the spring 94, an annular recess 96 around the upper end of the cylindrical space 90 communicating by openings 97 with the space above the valve. Sliding valve member 91 is provided with a central recess 99 opening to the space in the bottom of the valve and with a circular port 100 for cooperation with a circular port 101 in the valve casing to establish communication, when the valve is compressed, from the space 89, through said ports and the outer chamber 100 and the passages 97 to the top of the valve, whereby air can, in this position of the valve, pass through the valve into the eduction pipe 71, the space 99 in the valve opening into and communicating with the space 103 between the heads 68, 67, which space in turn communicates by a passage 105 with the external compressed air space 61 aforesaid. The operation of this form of the apparatus is identical with that above described for the forms shown in Figs. 1 to 7. Inasmuch, however, as this form of the invention is particularly intended for locations where the space for lateral support of the sections is limited, and inasmuch as the present system involves the separate support of each section so that any section may be removed at will without interfering with the others, I have provided special means for such independent support, consisting of a cable 107 extending down each side of the outer casing 65, said outer casing being flattened at the portions adjacent the cable to provide room therefor and being clamped or gripped to the cable by clamping devices 108, see Fig. 13, on the upper head of each section. Means are provided for raising or lowering these cables, not only to lift the column of sections for inspection or repair, but to enable the column to be adjusted in height, according to varying water level, this construction dispensing with the use of a series of valves 31 for each section: For this purpose the cables 107 may pass over pulleys 110 and be connected to any suitable draft means, not shown, for controlling the height of the column of sections.

To provide for the vertical adjustment or motion of the sections in adjusting to different heights of water in the sumps, a telescopic connection is preferably provided at the upper end of the well, the top section of

the well having a header 112 which connects the air space 69 with the interior of a tubular casing 113 extending upwardly therefrom and another tube 114 extends downwardly over said tubular casing 113 to form a telescopic joint, this joint being sealed by the water therein contained in an outer tubular member 115. Said member 114 is supported on a frame or derrick 118 and may be formed as a U-tube connected to the compressor, an intervening reservoir or cylinder 119 being provided, if desired. The space within the inner shell 66 of each section and outside the eduction pipes 70, 71 serves as a submergence element of the cell, this space at the upper end of the top-most section communicating by a lateral discharge spout 121 with a delivery chute or trough 122 pivoted at 123 to said spout and having its outer end mounted on roller or other means 124 to enable it to adjust itself to the varying heights of the column of well sections.

What I claim is:

1. An air lift pump comprising a plurality of cells connected in a vertically extending column, said cells being all of substantially the same height and each provided with an eduction leg and a submergence leg, said legs being connected together in a series comprising alternate downwardly extending submergence legs and upwardly extending eduction legs, said eduction legs being of greater height than the submergence legs, means at the upper end of each eduction leg for escape of air therefrom, a supply pipe for compressed air extending downwardly alongside the column of cells, a connection from said supply pipe to the lower end of each eduction leg, said connection provided with means for preventing escape of air therefrom into the eduction leg, said means being responsive to the pressure of fluid at the outlet of said connection to permit escape of air into the eduction leg when the same has become charged with water.

2. In an air lift pump, a column of cells connected in a series, the lower cell having an intake and the topmost cell having a discharge, means for independent supply of air to each cell for forcing the water therein to the next cell, means for escape of air from each cell to the outer air after it has performed the lifting operation, and valve means in the air supply connection for each cell for preventing the escape of air except when a predetermined head of water exists in the cell.

3. In an air lift pump, a plurality of cells connected in a series to form a column, an air supply pipe, independent connections from said pipe to the respective cells, an independent air escape means from each cell to the outer air, each of the supply connec-

tions to the cells including a valve provided with means for normally holding it in closed position, said valve being adapted to open under a predetermined head of water in the 5 cell to allow escape of compressed air into the cell, for the lifting operation.

4. An air lift pump adapted to operate under different conditions of immersion comprising a plurality of cells connected in 10 a series to form a column, means for independent supply of compressed air to the respective cells, means for independent escape of air from the respective cells to the outer air, and valve means connected in the air 15 supply connections for the respective cells, said valve means comprising a plurality of valves located at different heights and connected in series, each valve means provided with means for holding it in closed position, 20 and operating under a predetermined head in the cell above the valve means.

5. An air lift pump adapted to operate under different conditions of immersion comprising a plurality of cells connected in 25 a series to form a column, means for independent supply of compressed air to the respective cells, means for independent escape of air from the respective cells, valve means connected in the supply connections 30 for the respective cells, said valve means comprising a plurality of valves located at different heights and connected in series, each valve means provided with means for holding it in closed position, and operating 35 under a predetermined head in the cell above the valve means, whereby the valve means will operate simultaneously or singly under varying conditions of immersion, and means 40 acting on the respective valves for closing the same when the head exceeds a predetermined amount.

6. A pneumatic pumping apparatus consisting of a column of sections, one above another, each section comprising a shell having 45 an air discharge opening at its top and closed at the bottom, a pipe extending from the upper portion of each shell through the bottom of said shell and the top of the subjacent shell to the lower portion of said subjacent shell, an air supply pipe and connection therefrom leading into each shell, a nozzle pipe communicating with said air supply connection and extending upwardly within the aforesaid eduction pipe, and a 50 valve on said nozzle pipe provided with outlet means discharging into the eduction pipe, and a valve member movable in said valve to cut off communication through said outlet means, said valve member comprising a piston operated by the air pressure within the valve to move the valve to closed position, said valve member also comprising means for communicating water pressure from the eduction pipe to the said piston to operate in opposition to the water pressure to move the valve to open position when a predetermined head of water exists 55 above the valve, a spring acting on said valve member in opposition to the water pressure thereon to allow the valve to become closed when the head exceeds the predetermined working head.

7. A pneumatic pumping apparatus consisting of a column of sections, one above 60 another, each section comprising a shell

having an air discharge opening at its top and closed at the bottom, a pipe extending from the upper portion of each shell through the bottom of said shell and the top of the subjacent shell to the lower portion of said subjacent shell, an air supply pipe and connection therefrom leading into each shell, a nozzle pipe communicating with said air supply connection and extending upwardly within the aforesaid eduction pipe, and a valve on said nozzle pipe provided with outlet means discharging into the eduction pipe, and a valve member movable in said valve to cut off communication through said outlet means, said valve member comprising a piston operated by the air pressure within the valve to move the valve to closed position, said valve member also comprising means for communicating water pressure from the eduction pipe to the said piston to operate in opposition to the water pressure to move the valve to open position when a predetermined head of water exists above the valve.

8. A pneumatic pumping apparatus consisting of a column of sections, one above another, each section comprising a shell having an air discharge opening at its top and closed at the bottom, a pipe extending from the upper portion of each shell through the bottom of said shell and the top of the subjacent shell to the lower portion of said subjacent shell, an air supply pipe and connection therefrom leading into each shell, a nozzle pipe communicating with said air supply connection and extending upwardly within the aforesaid eduction pipe, and a valve on said nozzle pipe provided with outlet means discharging into the eduction pipe, and a valve member movable in said valve to cut off communication through said outlet means, said valve member comprising a piston operated by the air pressure within the valve to move the valve to closed position, said valve member also comprising means for communicating water pressure from the eduction pipe to the said piston to operate in opposition to the water pressure to move the valve to open position when a predetermined head of water exists above the valve, a spring acting on said valve member in opposition to the water pressure thereon to allow the valve to become closed when the head exceeds the predetermined working head.

9. A pneumatic pumping apparatus consisting of a column of sections one above another, each section comprising a shell having an air discharge opening at its top and closed at the bottom, a pipe extending from the upper portion of each shell through the bottom of said shell and the top of the subjacent shell to the lower portion of said subjacent shell, an air supply pipe and connection therefrom leading into each shell,

nozzle pipe communicating with said air supply connection and extending upwardly within the aforesaid eduction pipe and a valve on said nozzle pipe provided with 5 outlet means discharging into the eduction pipe and a valve member movable in said valve to cut off communication through said outlet means, said valve member comprising a piston operated by the air pressure with 10 in the valve to move the valve to closed position, said valve member also comprising means for communicating water pressure from the eduction pipe to the said piston to operate in opposition to the air pressure 15 to move the valve to open position when a predetermined head of water exists above the valve, and a spring acting on said valve member in opposition to the air pressure to move the valve to open position.

20 10. In an air lift pump, a column of cells connected in a series, the lower cell having an intake and the topmost cell having a discharge, means for independent supply of air to each cell for forcing the water therein to 25 the next cell, means for escape of air from each cell to the outer air after it has per-

formed the lifting operation, and valve means in the air supply connection for each cell for preventing the escape of air except when a predetermined head of water exists 30 in the cell, said valve comprising a casing formed with a cylindrical chamber and having nozzle outlets for supply of air to the cell, a piston slideable in said cylindrical chamber, means for admitting air pressure 35 from the air supply means to one side of said piston, means for admitting water pressure from the cell to the other side of said piston, said piston and casing having ports for establishing communication from the air 40 supply to the said nozzle outlets in an intermediate position of the piston and for cutting off such communication when at either side of said position and spring means operating oppositely on said piston. 45

In testimony whereof, I have hereunto set my hand at Los Angeles, California, this 23rd day of June 1909.

ADAM EDWARD CHODZKO.
